[57] CLAIM

The ornamental design for a shoe fastening member, as shown and described.

DESCRIPTION

FIG. 1 is a perspective view of a shoe fastening member showing my new design in a position of use;

FIG. 2 is a perspective view in a position of use in an unfastened state;

FIG. 3 is a top plan view thereof;

FIG. 4 is a left side elevational view thereof;

FIG. 5 is a front elevational view thereof;

FIG. 6 is a right side elevational view thereof;

FIG. 7 is a bottom plan view thereof;

FIG. 8 is a rear elevational view thereof; and,

FIG. 9 is a front elevational view thereof in an unfastened state.
